UNITED STATES PATENT OFFICE.

RAFFAELE BACCELLIERI, OF PHILADELPHIA, PENNSYLVANIA.

PRESS.

Application filed May 7, 1925. Serial No. 28,611.

My invention relates to presses especially designed for making macaroni, spaghetti, and noodles.

The presses now in use are of a complicated nature which are difficult to cast and require several machining operations which makes them costly.

The object of my invention is to provide a press of simple and strong construction which requires little machining, which may be quickly assembled and which may be produced at low cost.

These objects, and other advantageous ends which will be described hereinafter, I attain in the following manner, reference being had to the accompanying drawings in which

Figure 1 is a rear view of a press made in accordance with my invention,

Figure 2 a side view of the press shown in Figure 1,

Figure 3 a plan view of the press shown in Figure 1,

Figure 4 a section on line 4—4 of Figure 1,

Figure 5 a section on line 5—5 of Figure 3,

Figure 6 a section on line 6—6 of Figure 3, and

Figures 7 and 8 perspective plan views of elements forming part of my invention.

Referring to the drawings, 1 indicates a cylinder, 2 a die head having an opening 3 of smaller diameter than the cylinder and a counter-bore 4 to provide a shoulder 5 against which the lower end of the cylinder abuts. A die 6 rests on shoulder 5. An attaching head 7, has an opening 8 and a counter-bore 9 to provide a shoulder 10. The upper end of the cylinder fits counter-bore 9 and abuts shoulder 10. Die head 2 and attaching head 7 are connected to each other by tie bolts 11 passing through radially extending lugs on the heads. A bracket 12, pivoted to the attaching head by a bolt 13 and fastened thereto by a wing bolt 14, carries a screw 15 having on its lower end, a piston 16 adapted to move within the cylinder, and at its upper end a bracket 17 for receiving a handle 18.

For attaching the press to a support, I provide a yoked extension 19 on attaching head 7. This yoked extension is integral with the head and cast therewith.

Die head 2 and attaching head 7 being of plain shape may be easily die cast and the counter-bores and openings may be quickly

finished by machining. The cylinder is preferably cut from stock tubing and finished to fit the counter-bores. The heads and cylinder are then quickly assembled and fastened together by the tie bolts 11. Making and fastening these parts in such manner is inexpensive and produces a strong cylinder body for the press. Bracket 12, having screw 15 and its associated parts connected thereto, is pivotally fastened to attaching head 7 by bolt 13. The press assembled in this manner is ready for use.

To use the press, bracket 12 is swung to one side of head 7 to allow material, such as dough, to be placed in the cylinder. After the cylinder is filled and bracket 12 swung to its former position and fastened in place, screw 15 is screwed down to bring piston 16 against the dough and force it through die 6 which may be of a type for shaping the dough into macaroni, spaghetti or noodles. After use, the bracket with piston 16 is swung out of the way and die 6 removed from the cylinder. The die and cylinder may then be easily cleaned.

The press above described may be produced at low cost, is strong in construction, firmly holds the die in place, is highly efficient and may be easily cleaned.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A press including an attaching head having an opening, a die head having an opening, a cylinder clamped between the heads and communicating with the openings, a die secured in the opening of the die head, a piston bracket swingably mounted on the attaching head, and a piston in the bracket.

2. A press including an attaching head having an opening and a counter-bore, a die head having an opening and a counter-bore, a cylinder having its ends in the counter-bores clamped between the heads and communicating with the openings, a die secured in the opening of the die head, a

piston bracket swingably mounted on the attaching head, and a piston in the bracket.

3. A press including an attaching head having an opening and counter-bore, a die head having an opening and a counter-bore, a cylinder having its ends in the counterbores clamped between the heads and communicating with the openings, the opening of the die head being of less diameter than the cylinder to provide a shoulder, a die resting on the shoulder, a piston bracket mounted on the attaching head, and a piston in the bracket.

4. A press including an attaching head having an opening and a counterbore; a

bracket formed integral with the head for attaching the press to a support; a die head having an opening and a counterbore; a cylinder, having its ends in the counterbores, clamped between the heads and communicating with the openings; the opening in the die head being of less diameter than the cylinder to provide a shoulder; a die resting on the shoulder; a piston bracket swingably mounted on the attaching head, and a piston screw-threaded in the bracket.

In testimony whereof I have signed my name to this specification.

RAFFAELE BACCELLIERI.
